UNITED STATES PATENT OFFICE

1,978,642

FLOOR SECURING DEVICE

John A. MacLean, Chicago, Ill., assignor to
 MacLean-Fogg Lock Nut Company, Chicago,
 Ill., a corporation of Illinois

Application February 9, 1931, Serial No. 514,477

3 Claims. (Cl. 189—35)

My invention relates to floor-securing means and more particularly to means for securing the floor boards to a supporting sill and the like.

One of the objects of the invention is the provision of an improved construction of floor-securing clip in the form of strips which are adapted to be applied to the floor with less labor, and adapted to be manufactured with greater economy of material than the devices 10 of the prior art.

Another object of my invention is to provide a clip of the above type which is simple in construction and easily manufactured.

Another object of my invention is the provision of an improved method of fabricating the clips of the above type from a strip of metal.

Another object of my invention is the provision of an improved method of fabricating two clips from a single strip of metal by a simple shearing and forming operation without waste except for the holes punched.

Another object of my invention is the provision of an improved floor-securing strip having a body portion for engaging the supporting sill and laterally extending fastening flanges or clips, the spacing of which may be determined by the width of the flooring.

The above objects as well as others not particularly pointed out will appear in the following description taken in connection with the accompanying drawing.

For a more complete understanding of my invention reference may be had to the accompanying drawing illustrating a preferred embodiment 35 of my invention in which like reference characters in the several views denote like parts and in which:

Fig. 1 is a vertical cross-section through a portion of a floor construction to which my invention 40 may be applied.

Fig. 2 is a bottom plan view of Fig. 1 partially in section.

Fig. 3 illustrates a method of fabricating the floor securing device of my invention from a 45 strip of metal, and

Fig. 4 is a sectional view along the line 4—4 of Fig. 3 looking in the direction of the arrows indicated thereon.

Referring now to the drawing and particularly 50 to Figs. 1 and 2, the reference character 2 indicates a sill for supporting floor boards 3. The sill 2 is representative of a sill of a railway car which runs longitudinally thereof and usually comprises an I-beam or a U or channel beam 55 having a horizontal flange 4 on which are sup-

ported the floor boards 3. Formed in the floor boards 3 adjacent the edge of the sill flange 4 are bolt holes 5 spaced for the reception of the bolts 6 which extend through these bolt holes 5 and apertures in the fastening strip indicated 60 generally by the reference character 7 to secure the boards 3 to the sill 2 as clearly illustrated in Figs. 1 and 2.

The fastening strip 7 shown in securing position in Figs. 1 and 2 is one of two such strips 7 65 which may be fabricated from a single strip of metal of predetermined width and length and indicated generally by the reference character 8 in Fig. 3. The metal strip 8 is sheared along the zigzag line 9 between the respective edges 10 and 70 11 of the blank to form two similar securing strips. By means of a simultaneous forming operation the portions 12 and 13 adjacent the respective edges 10 and 11 are bent down out of the plane of the tooth-shaped formations or attaching 75 flanges 16 at the proper angle to engage beneath the sill flange 4 when placed in securing position as described hereinafter.

The shearing of the strip 8 along the zigzag line thus provides each of the fastening strips 7 with 80 a plurality of spaced clips or attaching flanges 16 joined together by the angularly disposed portions 12 and 13 extending longitudinally of the strip. The attaching flanges 16 are also provided with apertures or bolt holes 17 which may be punched 85 simultaneously with the shearing and forming operations to provide apertures for the passage of the bolts 6 when a strip is placed in fastening position as clearly illustrated in Figs. 1 and 2.

While I have described and illustrated a particular method of forming two metal fastening strips as 7 by means of a combined shearing and forming operation, it is apparent that the two fastening strips 7 may be first sheared, and subsequently, by means of a separate forming operation, each strip may be formed to provide the angular disposed portions without departing from the invention.

To secure the floor boards or planks to the sill 100 2 the fastening strip 7 is placed in position with its offset or angularly disposed portion 12 engaging beneath the sill flange 4 and the horizontal attaching clips or flanges 16 in contactual engagement with the underside of the floor boards 3 and in the plane of the upper face of the sill flange 4. The bolt holes 5 in the floor boards 3, adapted to receive the bolts 6, are spaced to place them in axial alignment with the bolt holes 17 in the attaching flanges 16 through which the 110

threaded ends of the bolts extend for the reception of the nuts 20.

The bolt 6 preferably includes a head 21 having a convexly curved top surface and a bottom surface 22 which tapers in thickness from the shank 23 out toward the edge of the head 21. The bottom surface 22 of the head is provided with an integral annular ridge or bead 24 of V-shaped cross-section and an annular groove 25 next to the shank 23. As the nut 20 is threaded home by means of a wrench or other suitable tool, the bolt-head 21 is drawn into the bolt-hole 5 and embeds itself into the surface of the lumber about the bolt-hole 5 and also causes the wood adjacent the inner surface of the ridge 24 to be forced against the shank 23 of the bolt 6 and into the groove 25 to form a substantially water-tight seal between the bolt-head 21 and the floor board 3. The nut 20, as provided, is of the self-locking type which, when threaded home, causes the threads of the nut to be forced into clamping engagement with the complementary threads of the bolt 6.

For a more complete understanding of the bolt construction just described, reference may be had to a copending application Serial No. 423,011, filed January 24, 1930.

The strip just described and its application to a floor structure shown in Fig. 1, may be made of any desired length and the stamping of two such strips from a single strip of metal eliminates any waste of material. The offset angular portion of the strip, which extends longitudinally thereof, provides a substantial contacting surface between it and the under face of the sill flange 4 while the horizontally disposed fastening flanges 16 engage the under side of the floor boards to provide as many bolt openings as are desired. Thus the provision of a plurality of bolts which pass through the fastening flanges of the strip prevents displacement or rotation of the strip when in securing position. The strip also permits easy assembly when attaching the same to the sill and the floor boards, and, by reason of the fact that a number of clips are carried by a single strip, the structure of the clip can be made more simple and a multiplicity of clips can thus be applied at the same time.

While I have illustrated and described a preferred embodiment of my invention and illustrated and described the same associated with a particular floor-supporting structure, I wish

it understood that the clip of my invention is applicable to other uses, and that changes and modifications will suggest themselves, I therefore aim to cover all such changes and modifications as come within the spirit and scope of the appended claims.

I claim:

1. A securing clip for railway car floors comprising an elongated strip of sheet metal formed with a body flange adapted to engage one of the flanges of a structural steel frame member of the floor frame, said body flange having a plurality of regularly spaced floor engaging flanges, said floor engaging flanges being located to engage successive flooring members and being provided with apertures for receiving floor bolts and said strip having offset portions between said body flange and each of said floor engaging members.

2. A securing clip for railway car floors comprising an elongated strip of sheet metal formed with a body flange adapted to engage one of the flanges of a structural steel frame member of the floor frame, said body flange having a plurality of regularly spaced floor engaging flanges, said floor engaging flanges being located to engage successive flooring members and being provided with apertures for receiving floor bolts and said strip having offset portions between said body flange and each of said floor engaging members, said floor engaging flanges being substantially trapezoidal in form and tapering from said body flange toward the outer edge of said floor engaging members, the space between said floor engaging members being substantially similar in shape and size to each of said floor engaging members.

3. In a railway car floor structure, the combination of a sill having a floor supporting flange with a floor comprising a plurality of transverse members supported upon said sill flange, said members having apertures for bolts, a longitudinally extending floor securing strip, said strip having a plurality of outwardly projecting flanges for engaging said floor members and located adjacent the apertures in said floor members, the flanges having apertures for receiving said bolts, said floor strip being offset downwardly and laterally and having a continuous body engaging under said sill flange, and a plurality of bolts extending through said floor members and the flanges of said securing device and clamping said securing device and floor to said sill flanges.

JOHN A. MACLEAN.
